UNITED STATES PATENT OFFICE.

JOSEPH R. H. HINTON, OF BALTIMORE, MARYLAND, ASSIGNOR TO THE VIA-
DUCT MANUFACTURING COMPANY OF BALTIMORE CITY, OF SAME PLACE.

MAGNETO-ELECTRICAL ALARM.

SPECIFICATION forming part of Letters Patent No. 292,311, dated January 22, 1884.

Application filed November 12, 1883. (No model.)

To all whom it may concern:

Be it known that I, JOSEPH R. H. HINTON, of Baltimore, in the State of Maryland, have invented certain new and useful Improvements in Magneto-Electrical Alarms; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to improvements in magneto-electric fire-alarm signal-boxes in which the mechanism is operated by an automatic motor.

The objects of the improvement are to automatically regulate the speed of the motor, and consequently of the break-wheel driven thereby, in order that the makes and breaks may be separated by proper intervals to insure distinctness in the signals turned in; to provide for maintaining the break-wheel in position while the motor is being wound up; to prevent the motor from running except when it is started at the proper time, and to provide for an initial movement of the mechanism in assistance of the weight or spring when a signal is to be given. With these objects in view my improvement consists in certain novel constructions and combinations of devices, which will be fully understood from the following particular description in connection with the accompanying drawings, in which—

Figure 1 is a vertical section of a signal-box, showing a side elevation of the interior mechanism. Fig. 2 is a similar view, showing an elevation of the mechanism on the side opposite to that shown in Fig. 1. Fig. 3 is a horizontal section of the box and plan view of the interior mechanism. Fig. 4 is a similar view, showing in plan the key-retaining device within the box.

The letter A indicates the frame which supports the mechanism inside of the box B.

C is the main driving-shaft, carrying a barrel, D, upon which is wound a cord, E, operated by a weight, E'. This barrel is connected with the main gear-wheel F by the ordinary

pawl and ratchet common in this class of motors, and this main gear-wheel meshes with a pinion on a shaft, f, carrying a gear-wheel, f', which in turn meshes with a pinion on a shaft, f'', carrying a gear-wheel, f'', which meshes with a pinion on the shaft g of the rotary armature G, arranged between the poles of a permanent magnet, H, said armature being connected up in a well-known manner, to send a current through an electro-magnetic bell, I, and over the wires P and N, which are to be connected with the line-wire in the usual manner.

K indicates a signal or break wheel, of usual construction, having raised portions or teeth arranged to make contact with a spring contact-finger, J, for sending the signals, in a manner well understood by persons familiar with electrical fire-alarm mechanism. This break-wheel is mounted on one end of a short shaft, having on its other end a gear-wheel, L, which meshes with a pinion, l, on the main shaft, from which the break-wheel derives its rotary motion.

The parts which I have now referred to are old in construction and relative arrangement; but when such parts only are used there are defects in the operation of the mechanism, which it is the object of my improvements to overcome. For instance, when the cord is first wound upon the drum and the mechanism started into operation, the weight will cause the main shaft to move at first comparatively slowly, and as it continues to run the acquired momentum results in an increasing rapidity of revolution in the break-wheel, so that the intervals between the signaling-impulses become less and less toward the end of the signal, thus giving rise to confusion. In order to overcome this difficulty I arrange a stationary disk, M, attached to the frame A by side lug and screws, as shown in Fig. 2, having an annular flange, m, concentric with the shaft g of the armature. This shaft extends centrally through the disk M, and has pivoted to it, at diametrically-opposite points, two curved arms, o o, arranged to be swung outward by centrifugal force. These arms are so weighted that when the rotation of the armature-shaft reaches the desired speed they will fly outward and impinge against the flange m with such friction as

to prevent that speed from being exceeded, and a uniform speed of rotation is thus secured in the break-wheel, which, as it will be remembered, is connected with the armature-shaft by intermediate gears. The position in which the break-wheel stops after giving a signal is that from which it should start on giving a subsequent signal; but unless some provision is made for holding it in such position it is liable to be moved therefrom during the winding up of the cord, or a spring, if the latter should be used to give the motive power. I have therefore contrived an automatic brake mechanism which will prevent all movement of the train while the barrel is being wound up. The barrel has projecting from one side a sleeve-shaft, C, which fits over the main shaft C and projects outwardly beyond the frame A, as shown in dotted lines, this projecting portion being squared to receive a key, Q, the barrel q of which has a corresponding socket to fit over this projecting squared portion of the barrel-shaft. To the side of the frame A from which the barrel-shaft projects is pivoted a bent lever having a long arm, R, to the outer end of which is firmly secured at one end a transverse rod, r, having pivoted upon its other end a brake-shoe, S, arranged to bear upon the periphery of the gear-wheel f^3 , which meshes with the pinion upon the armature-shaft. The other arm, R', of this bent lever curves over the squared projecting portion of the barrel-shaft in such position that when the barrel or tube of the key is placed upon this shaft, said tube will force the arm R' upward against the tension of the spring t, and consequently the arm R will be swung downward, and the brake-shoe carried by the rod r will be pressed against the periphery of the wheel f^3 with such force as to prevent the train from moving as long as the key is in position for winding up the barrel, and thus closing the winding operation, and the break-wheel, which is connected with the train, will be absolutely prevented from moving from the position in which it stops prior to the commencement of the winding. The tip of the key-tube should be beveled in order to facilitate its passage under the arms R'.
 In the present instance a weight is used to give the motive power, and this weight and its cord will obviously commence to operate the train as soon as the key is removed, unless means are provided to prevent the movement of the train until such time as the signal is to be given. I have, therefore, placed upon the barrel-shaft a ratchet-wheel, u, with which engages a pawl, u', pivoted to the frame A, and provided with a thumb-piece, u², by which it may be raised. This pawl prevents the operation of the train by the weight as long as it remains engaged with the ratchet-wheel; and the first act, therefore, which is necessary in starting the train is to throw this pawl back out of engagement with the ratchet-wheel. This being done the weight may descend to

operate the train, and in order that it may have a sufficient downward movement, the floor or bottom of the box is provided with a movable section, b, which is attached to the door b', so that when the door is opened this section will be removed from under the weight and give it free passage downward. It will be understood that, after a signal is sent, the train is to be wound up ready to give a subsequent signal when required, the necessary operation for giving such signal being, usually, simply to open the box and throw back the pawl u', as before explained. It may, however, sometimes be necessary to give the train an initial movement in assistance of the weight, as it is not desirable to use a weight so heavy that it will always promptly start the train. A much smaller weight will suffice to efficiently operate the train after it is once started than would be required to start it promptly after the detaining-pawl is thrown back. In order to give the train an initial movement, I have arranged under the shaft f, which carries the gear-wheel f^3 , a shaft, f⁴, carrying a pinion, f⁵, meshing with said gear-wheel. This shaft has a projecting portion provided with a thumb-piece, w, by which it may be turned, and also with a ratchet-wheel, w', with which engages a detent-pawl, w². On opening the box and turning back the detent-pawl w², the person sending the signal should turn the thumb-piece w in the direction indicated by the arrow, thus causing the pinion f⁵ to turn the gear-wheel f³ and give an initial movement to the train. A slight initial assistance only is needed, as the train being once started, the weight will continue it in operation until it runs down. In order that the key for winding up the barrel may not be displaced or lost, it is desirable that it should remain in the box; and in order that it should so remain I have provided the door of the box with spring-finger y, (shown in dotted lines,) which, when the door is closed, will catch over a shoulder, q', formed on the key, and when the door is opened will automatically draw the key off the winding-shaft and release the brake. These spring-fingers will support the key when it is not in use, and it may be readily detached from said fingers when required for winding up the train.

Any of the suitable and well-known devices may be used for determining the number of revolutions to be made by the break-wheel in giving each signal.

Having now described my invention and explained the operation thereof, I claim—

1. The combination, with the train of gearing operating the signaling device, of a brake arranged for application to one of the wheels of such train, and adapted to be thrown into frictional contact therewith by the insertion of the winding-key, substantially as shown and described.

2. The combination, with the train having the barrel-shaft projecting and adapted to receive a key, of the pivoted bent lever having

an arm, R, carrying a brake arranged for application to one of the wheels of the train, and an arm, R', arranged adjacent to the projecting key-receiving portion of the winding-shaft, and in such position as to be moved by the key for applying the brake, substantially as shown.

3. The combination, with the winding barrel and its shaft, of the auxiliary ratchet-wheel ¹⁰ u and the pivoted pawl u', provided with a thumb-piece, substantially as described, and for the purpose set forth.

4. The combination, with the actuating-weight and the train, of the shaft f⁴, carrying ¹⁵ the pinion f⁵, meshing with one of the wheels of said train, and provided with a thumb-piece by which it may be turned, whereby an initial movement is given to the train, overcoming

its inertia, and supplementing the action of the weight, substantially as described. ²⁰

5. The combination, with the train of gearing, the key-winding shaft, and the brake-lever arranged with respect thereto, as described, of the key-supporting device affixed to the box-door in juxtaposition to the winding-shaft, ²⁵ whereby the brake is automatically released upon opening the door, substantially as shown and described.

In testimony that I claim the foregoing as my own I affix my signature in presence of two ³⁰ witnesses.

JOSEPH R. H. HINTON.
